CLAIM

The ornamental design for a deskspool, as shown and described.

DESCRIPTION

FIG. 1 is a perspective view of a deskspool, according to a design of the present invention.

FIG. 2 is a front view of the deskspool of FIG. 1.

FIG. 3 is a rear view of the deskspool of FIG. 1.

FIG. 4 is a left side view of the deskspool of FIG. 1.

FIG. 5 is a right side view of the deskspool of FIG. 1.

FIG. 6 is a top view the deskspool of FIG. 1.

FIG. 7 is a bottom view of the deskspool of FIG. 1; and, FIG. 8 is a perspective view of the deskspool of FIG. 1.

The broken line showing of portions of the deskspool is for illustrative purposes only and forms no part of the claimed design.
